UNITED STATES PATENT OFFICE.

SCOTT L. NORVIEL, OF LOS ANGELES, CALIFORNIA.

INDUCTANCE COIL.

Application filed February 10, 1926. Serial No. 87,229.

My invention relates to a construction of an inductance coil, and a support therefor, and has for its principal object the provision of an improved coil and supporting structure 5 of a character which will be highly efficient in use, and inexpensive to manufacture.

One of the principal objects of my invention is the provision for an improved construction, of the character described in which 10 the inductance coils are so wound and mounted in relation to the supporting members as to reduce or tend to reduce to a minimum, the losses of electrical energy due to dielectric leakage by absorption, and inter-turn capacity. Also, I propose a construction of the 15 character described, so designed as to diminish losses of electrical energy, and eliminate the undesirable effects resultant from such losses when these inductances are employed as 20 instruments in radio apparatus, as tuning inductances, radio frequency transformers, vario-couplers and the like.

Other objects will appear hereafter.

The invention consists of the combinations 25 and arrangements of parts hereinafter described and claimed, and will be best understood by reference to the accompanying drawings which form a part of this specification, and in which,

30 Fig. 1, is a side elevational view of a construction made in accordance with my improvements; Fig. 3 is an end elevation thereof; and Fig. 2 is a cross sectional view, taken substantially on line 2-2 of Fig. 1.

35 Figure 3 represents the end view of the coil shown in Figure 1. This illustrates more fully the position and construction of the primary inductance 15, Fig. 1. The slotted ring 14 is supported within the ring 1 by the 40 pressure of the flattened ends of the beams 16 and 17. In this slot the coil 15 is wound consisting of number of turns of insulated wire; the inner lead being taken off at 15' and the outside lead at 15''. Electrical connection is made to lugs 13-13 by bolts 19-19.

45 It will be readily understood, by those familiar with the art of radio telegraphy and telephony, that losses of electrical energy with their attendant undesirable effects, are 50 in a majority of cases largely due to losses in the inductance coils caused by winding the wire composing these inductances with sufficient spacing between the consecutive turns and upon and between an inefficient dielectric. Radio frequency currents, especially 55 those of higher frequencies, tend to leap or

jump across from turn to turn of an inductance, unless these turns are separated by a distance greater than that provided by the usual layer of insulation upon wire in common use, and in all dielectrics a certain amount of energy is lost, depending upon the amount of material used and the manner and method of construction.

Heretofore, it has been customary to either 65 wind such inductance coils upon a solid cylindrical or prismatic core-form, or in a manner so that the coil will depend upon the support given by one turn to another for sufficient rigidity to make its use practical, or to 70 clamp or cement the turns in position one to another upon a supporting medium, so that uniform spacing and rigidity might be maintained. These structures are costly, inefficient, and unless wound upon substantial tubing, are too delicate for practical use, and furthermore, the material usually used and obtainable for these cylindrical forms is a 75 poorer dielectric for these purposes than air.

By my invention I provide a device, manner and method of construction by which 80 these coils may be wound upon a minimum of solid dielectric material with turns separated by an air gap and constructed with relative parts such that the whole structure is substantial and rigid.

85 Referring to the accompanying drawing, it will be seen that the construction includes two end-rings 1 and 2, connected at equi-spaced intervals by cross-beams 16 and 17 90 secured to the inner periphery of said end-rings by machine screws 6, 7, 18, 19 and 20. These rings are made of bakelite or other suitable insulating material, while the beams are preferably of celluloid or other pliable 95 elastic insulating material. I prefer to make these beams by bending or folding a thin flat strip of insulating material such as celluloid at an angle which may either approximate the right angle as illustrated in Figures 1 100 and 2 or be an obtuse angle as illustrated in Figure 3. When constructed as in Figures 1 and 2, the beam is compound and composed of two strips 16 and 17, the two sides of which bear upon each other, thus forming a 105 T-beam. Upon and around the outer sides of these beams wire composing an inductance coil in helix form is wound, and the turns thereof securely cemented to each beam, or half thereof, with celluloid or other suitable 110 cement.

In the optional form shown in Figure 3,

the wire 3 is wound in prismatic form and the cross-beams 16' consist of strips of thin celluloid or other suitable insulating material cemented on the inside of the coil at the angles of the prism faces, the center of the strip conforming to the inside of the edge of the prismatic form and the sides of the fold thus formed conforming to the sides of the prism.

From the foregoing description and drawing, it will be seen that in either form the structure of the device is made very firm and solid by reason of the angular bending of the strips 16, 17, and 16', and the cementing of the turns of wire to them, and that thereby I have provided a very simple inexpensive form of construction which will permit the consecutive turns to be wound with an air space between them, and yet remain structurally strong and rugged, and in which air is employed as a dielectric between the turns and for the most part of the winding, and in which solid dielectric supports for the coils are greatly reduced. Thus there is a lessening of losses of electrical energy, and consequently a more efficient piece of apparatus is made, which makes possible a substantial improvement in the operation of a radio set into which it may be incorporated, evidenced both by the distance-getting powers and selectivity of the set, and which at the same time is economical and inexpensive to manufacture. By combining the above described structure as a secondary with the slot-wound primary 15, above described, the entire device becomes an exceedingly efficient transformer for radio frequency currents due to the fact that there is a maximum of magnetic coupling between the primary and secondary windings of the inductance, and a minimum of capacitative, (out of phase) coupling. The advantages of this are obvious to those familiar with the art.

While I have described and illustrated the preferred form of construction for carrying

my invention into effect, it is obvious to those skilled in the art that this is capable of variation or modification without departing from the fundamental idea or spirit thereof, and I desire, therefore, to be limited only by the following claims:

1. In combination, in a device of the kind disclosed, a helix of conductive material, a pair of end rings of dielectric material, a plurality of relatively thin strips of flexible dielectric material supporting said helix and extending longitudinally thereto, a longitudinal right angle fold along said strips, said strips being placed in pairs with their supporting sides extending in opposite directions along the inner periphery of said helix while their axially extending sides abut together, means for cementitiously attaching the turns of the helix to the supporting side of said strip, means for supporting the entire device and attaching to a base board.

2. In a device of the kind disclosed, a helix of conductive material, a pair of end rings of dielectric material approximately the size of said helix, a plurality of relatively thin strips of celluloid supporting said helix and extending longitudinally thereto, a longitudinal right angle fold extending along said strips, means for attaching the ends of said strips to said end rings so that one flat side rests against the inner periphery of the helix while the other extends inwardly toward the axis thereof, said strips being placed in pairs their sides supporting the helix extending in opposite directions along the inner periphery of said helix, while their axially extending sides abut together, means for cementitiously attaching the turns of the helix to the supporting side of said strip, means for supporting the entire device and attaching to a base board.

In testimony whereof, I have signed my name to these specifications.

SCOTT L. NORVIEL.
